UNITED STATES PATENT OFFICE.

RALPH C. SIMMONS, OF BEVERLY, MASSACHUSETTS, ASSIGNOR TO UNITED SHOE MACHINERY COMPANY, OF PATERSON, NEW JERSEY, A CORPORATION OF NEW JERSEY.

HOOK AND EYELET SETTING MACHINE.

1,146,028.

Specification of Letters Patent.

Patented July 13, 1915.

Application filed August 4, 1909. Serial No. 511,146.

To all whom it may concern:

Be it known that I, RALPH C. SIMMONS, a citizen of the United States, residing at Beverly, in the county of Essex and State 5 of Massachusetts, have invented certain Improvements in Hook and Eyelet Setting Machines, of which the following description, in connection with the accompanying drawings, is a specification, like reference characters 10 on the drawings indicating like parts in the several figures.

This invention relates to machines for setting eyelets, lacing hooks or studs, rivets or similar fasteners, and more particularly to 15 machines for setting two different kinds of fasteners, as eyelets and lacing hooks, in boots and shoes.

An important object of the invention is to provide a machine for setting two kinds of 20 fasteners of the characters referred to which will be capable of operating automatically to first set a predetermined number of one kind of fasteners, as eyelets, and to then set a predetermined number of another kind of 25 fasteners, as lacing hooks.

Another object of the invention is to provide, in such a machine, automatic mechanism to stop the operation of the fastener setting devices after a predetermined number 30 of either kind of fasteners has been set, and which is furthermore, under manual control, whereby the operation of such devices may be stopped at any point desired by the operator independently of the automatic mechanism. In connection with this 35 feature of the invention, if the machine is constructed to set eyelets and lacing hooks, the arrangement is such that the number of either of these fasteners which the machine 40 will set may be controlled by the operator.

Another object of the invention is to provide, in a machine of the character referred to, means for determining the distance that the eyelets and the lacing hooks shall be set 45 from the edge of the stock, which means is automatically controlled in such manner that the eyelets may be set at a different distance from such edge than the lacing hooks, and, if desired, certain of the eyelets may be set 50 at a greater distance from such edge than other eyelets. Preferably, the means referred to includes a gage whose location to variably determine the position of the edge of the stock relatively to the setting devices 55 is governed by any one of a set of pattern

cams which are under the control of the operator.

The invention is shown as embodied in a machine provided with a setting device for eyelets and a setting device for lacing hooks, 60 and a feature of the invention consists in providing in connection with each of such devices a coöperating anvil, and two punches, one of a size appropriate for eyelets and the other of a size appropriate for 65 hooks, the punches being so arranged that either of them may be positioned over the punch anvil and the mechanism will act to cause the punch which is in operative position to first move downwardly to punch the 70 stock, and to then move laterally to feed the stock the proper distance to locate the punched hole under the eyelet set, or the hook set, as the case may be.

In connection with the mechanism that 75 effects the setting of a predetermined number of eyelets and a predetermined number of lacing hooks, the machine embodies automatically operating devices which are so constructed as to move the eyelet punch into 80 operative relation with its anvil and the hook punch out of operative relation therewith when the eyelet set is rendered operative and the hook set is rendered inoperative, and vice versa. As the eyelet set and 85 the hook set respectively, occupy different lateral positions relatively to the position occupied by the punch which may be in operation, mechanism is provided for automatically changing the terminal point of 90 the punch in feeding the stock, so that such point will be located in line with the eyelet setting plunger when eyelets are to be set in the stock, and in line with the hook setting plunger when hooks are to be set there- 95 in. Preferably this mechanism includes an adjustable member connecting a feed slide, or table, with the carrier for the punch the member being actuated in such manner as to move the punch-carrier in one direction relatively to the feed slide prior to the operation of the eyelet set, and in the opposite direction prior to the operation of the hook set.

As it is frequently desirable to space the 105 hooks a given distance apart on the stock and the eyelets a different distance apart, it being the usual practice to set the eyelets closer together than the hooks, a feature of the invention lies in the provision of an im- 110

proved mechanism, automatically controlled, for determining the distance that these fasteners shall be spaced from one another when set, such mechanism being also under 5 manual control, whereby the operator may, under one adjustment, so influence the automatic mechanism as to vary the spacings of the fasteners controlled thereby, and under another adjustment may vary such spacings 10 in a manner which will be wholly independent of the automatic mechanism.

The hook setting device and the eyelet setting device, together with their co-operating anvils, are preferably located side by side 15 and are given the necessary movements to cause them to set the fasteners in the stock by two oppositely moving actuating members. In this connection, an important feature of the invention comprises an improved 20 construction and arrangement of parts, whereby, when the eyelet setting devices are rendered operative the hook setting devices are rendered inoperative, and vice versa. In the preferred construction, a plurality 25 of locking devices are arranged in connection with the plungers carrying the setting devices and their anvils in such manner that when the locking devices are moved in one direction the eyelet setting device and its anvil 30 are locked to the actuating members, and the hook setting device and its anvil are locked to the frame of the machine; and when the locking devices are moved in the opposite direction the hook setting device 35 and its anvil are locked to the actuating members, and the eyelet setting device and its anvil are locked to the frame of the machine.

Another feature of the invention comprises 40 an improved arrangement for supporting the hopper for containing the eyelets, whereby it may be rocked or oscillated, together with its raceway, to enable the setting device to pick the eyelets from the end 45 of the raceway as it moves toward setting position, the parts being so constructed as to permit the hopper and raceway to be easily removed in order that another hopper and raceway adapted for a different size or style 50 of eyelets may be substituted therefor.

Other features of the invention, including important combinations of parts and details of construction, will be hereinafter more specifically described and claimed.

55 Figure 1 is a front elevation of a machine embodying the present invention. Fig. 2 is a left side elevation of the machine shown in Fig. 1, the cover of the eyelet hopper being partly broken away. Fig. 3 is a transverse 60 sectional view of the lower part of the machine shown in Fig. 1, looking toward the right. Fig. 4 is a right side elevation of the machine shown in Fig. 1. Fig. 5 is a view in elevation, partly sectional, of the front 65 part of the machine with the cover removed

to show the main power shaft, its cams, and the clutch. Fig. 6 is a transverse sectional view taken through Fig. 5, showing parts of the clutch-controlling mechanism. Fig. 7 is a sectional plan view of the lower part of 70 the machine, illustrating the main power shaft, the pattern-cam shaft and its cams and connections. Fig. 8 is a transverse sectional view on the line α — α , Fig. 7, looking toward the left. Fig. 9 is a detail view, 75 showing in plan the punches and some parts of the controlling devices therefor illustrated in Fig. 3. Fig. 9^a is a detail view, showing the segmental gears for controlling the position of the punches. Fig. 9^b is a view in 80 transverse section on the line y — y , Fig. 9. Fig. 10 is a rear elevation of the machine shown in Fig. 1. Fig. 11 is a detail view, illustrating the inside of the eyelet hopper. Fig. 12 is a transverse sectional view of the 85 eyelet hopper. Fig. 13 is a plan view of the parts shown in Fig. 14 below the work support, which is partly broken away. Fig. 14 is a detail view, showing the hook set and the upper part of its plunger, together with 90 certain parts operating in connection therewith. Fig. 15 is a detail view of the work support and the hook-positioning slide. Fig. 16 is a detail view of the hook raceway and separator. Fig. 17 is a view in 95 elevation of the end of the hook raceway. Fig. 18 is a plan view of the work support, the edge gage, the hook set and the hook-positioning slide. Figs. 19, 20, 21 and 22 are detail views, partly sectional, illustrating 100 the several positions of the keys in locking the plungers carrying the sets and their anvils to the actuator, and to the frame of the machine. Fig. 23 is a right hand side elevation, partly sectional, of the machine 105 shown in Fig. 1, the plane of section being taken to the right of the feed table and its operating mechanism in order to show said parts. Fig. 24 is a detail view showing in plan the feed table, a part of the edge gage, 110 the punch carrier, and the adjusting devices therefor. Fig. 25 is a rear elevation of Fig. 24.

The numeral 252 indicates the main frame or casing which supports, and partly 115 encloses, the several elements of the machine herein shown as embodying my invention. The frame sustains, in suitable bearings provided therefor in its front portion, (see Fig. 5), a power shaft 1 to which are keyed or otherwise fastened a number of cam disks having grooves or ways for operating the clutch, the presser foot, the eyelet raceway, the punch, the hook-releasing lever, the setting devices and the feeding mechanism. 120 The power shaft also carries the clutch member 231, and the loose pulley 232. All of these parts will be referred to and more particularly described hereinafter.

Suitably located in bearings in another 130

part of the frame, preferably to the rear of the power shaft 1, (see Figs. 6, 7 and 8), is a shaft 8, carrying a number of gears 11, 12 and 13, which mesh with a like number of 5 gears on a shaft 253, forming part of a train connecting a gear 23 on the shaft 1 with the gears 11, 12 and 13. The shaft 8 carries six sets of pattern cams, designated, respectively, by the letters *a*, *b*, *c*, *d*, *e* and *f*, each of which, in the machine illustrated, comprises three cams so designed as to effect in the mechanism controlled thereby, as will be hereinafter described, a definite operation. These cams are herein 10 shown as being in the form of thin disks and are fastened rigidly to the shaft by a series of spacing collars, or equivalent means, through a key 10, so as to rotate therewith. The shaft 8 is mounted for longitudinal sliding movements in its bearings 15 in the frame 252, and in the three gears 11, 12 and 13, and carries a feather key 14, whereby, when the shaft is moved to position any of the pattern cams in the sets that 20 may be selected to impart certain predetermined operations to the several mechanisms, opposite their appropriate cam levers, the feather key will enter a coöperating recess in that one of the three gears which has a 25 suitable number of teeth to cause the shaft 8 and its cams to rotate at the proper relative speed to the shaft 1.

The shaft 8 and pattern cams are manually movable in a longitudinal direction 30 through a lever 15, pivoted to the frame at 19, and having its inner end forked to embrace the end of the shaft, which is provided with an abutment outside of the forked end of the lever. The outer end of 40 the lever is formed as a handle, and has pivoted thereto at 20 a latch lever 16, carrying a pin 17 to coöperate with a series of holes 18 in a bracket fast to the frame of the machine, whereby the lever may be held 45 in any one of the three positions to which it is moved in longitudinally adjusting the shaft 8 and the pattern cams. The pattern cams are so formed that at one point in all the cams the distance measured from the 50 center of the shaft diametrically outward is the same, and, when the shaft in its rotation carries the cams so that this point coincides with the several cam levers, the parts are in position to be shifted longitudinally. In 55 order to insure that it shall be shifted at this point the shaft 8 is provided with a series of disks *g*, which are fast thereto, and have in their peripheries a series of alined openings arranged to register with a 60 plate 21 secured to the frame by a screw 22, when the shaft has reached the position appropriate for such longitudinal movement. At any other point in the revolution of the 65 shaft the plate 21 will lie in one of the spaces between the adjacent faces of two of

the disks, and hence prevent any shifting of the shaft.

The gear 23 is mounted on a hub which carries an internal spline or feather 24, to enter a groove in the shaft 1 in order that 70 it may be constrained to rotate with the shaft, while being free to slide longitudinally thereon, to permit the gear to be moved into or out of mesh with the train of gears connecting the shaft 1 with the 75 shaft 8; and the hub is formed with grooves 25 and 26, to be engaged by a pin 27, slideable in the frame of the machine, which holds the gear in or out of meshing engagement with the train. By this arrangement, 80 if the gear 23 is moved out of mesh, the shaft 8 and pattern cams are free to be rotated manually, which, under certain conditions, may be found desirable. In order to effect this operation a lever 28 is secured 85 to the end of the shaft 8 by a nut, as shown, and has one of its ends connected by a spring 30 to a fixed point on the frame of the machine, and its opposite end connected, through a rod or other suitable connection 90 29, with a treadle, or equivalent operating device. A plate 31 is secured to a collar on the shaft 8 to coöperate with a pin 32, which is slidably mounted in the bracket to which the plate 21 is fastened. When it is 95 desired to rotate the shaft manually by the lever 28 the pin may be projected so as to intersect the path of movement of the plate 31, the arrangement of these parts being such that after the shaft 8 is rotated sufficiently to cause the pattern cams to actuate the mechanisms controlled thereby, the treadle may be released and the spring 30 will act to rotate the shaft reversely and restore it to its normal position of rest, the 100 plate 31 coming in contact with the pin 32 to prevent further rotation of the shaft when it reaches the position where the openings in disks *g* aline with the plate 21. The spring 30 and treadle rod 29 are in free 105 detachable engagement with the ends of the lever 28, as by means of hooked terminals which enter apertures in the lever, whereby, when the shafts 1 and 8 are to be connected through the train of gears in order that the 110 pattern cams shall be caused to operate automatically, the spring and rod may be disconnected from the lever and the latter will simply turn idly as the shaft rotates.

With the construction above described, 120 the operator may, by a few simple manipulations, connect the pattern cams with the power shaft of the machine in order that they may be operated automatically in timed relation with the parts whose operations are 125 controlled by the cams carried on the shaft 1, or he may operate the pattern cams through any desired arc of movement independently of the movements of the parts controlled from the shaft 1.

Referring to Figs. 1, 4, 7, 10, 11 and 12, the hub carrying the gear 23 is provided with a fast pulley 249, which, through a belt 250 and fast pulley 251, serves to rotate a short shaft mounted in bearings on the frame of the machine and carrying a one-toothed gear 271, which meshes with a gear 253 fast on a shaft 254. This shaft carries a picker plate 66, in a hopper 65, which is supported on the frame of the machine and may contain lacing hooks. The shaft 254 is journaled in and extends through the hopper 65 and upon its end is secured a bevel gear 255, which meshes with a bevel gear 256, secured to the end of a shaft 257, journaled in and extending through a hopper 40, to contain eyelets, said shaft carrying, within the hopper 40, a picker plate 45. The frame 41 of this hopper is constructed at a suitable point in its periphery with a socket 43, and at another point, diametrically opposite thereto, with a projection 42, to coöperate, respectively, with a pin 44 movably mounted in a bracket which projects from the machine frame, and a socket 420, formed in another bracket which also projects from said frame, said parts constituting pivotal bearings for the hopper 40. As the centers of the pin 44 and socket 420 coincide with a line whose direction is inclined to the base line of the hopper 65, the hopper 40 will be sustained angularly thereto, as shown in Fig. 10. The raceway 50 is rigidly secured to its hopper 40, and upon removal of the pin 44 from the socket 43, the hopper may be lifted from the socket 420, and another hopper and raceway, adapted for a different kind or size of eyelets, substituted therefor.

The eyelets which are to be fed to the eyelet setting devices are separated from those in the bottom of the hopper and discharged into the raceway 50 by the picker plate 45, whose construction may be the same as the picker plate used for the lacing hooks. The bottom 46 of the hopper is preferably externally threaded as shown at 47, (Fig. 12), to engage an internal thread in the frame 41, in order that the space between the picker plate and the bottom of the hopper may be adjusted to agree with the size of any desired eyelet, it being understood that the flanges of some eyelets are thicker than others. The picker plate being caused to revolve through the connections described, eyelets will be carried up on that part thereof indicated by the numeral 48, and those whose flanges have not been caught between the bottom of the hopper and the plate will, owing to the inclination of the hopper, fall back into the lower part thereof. The eyelets which have been caught by the plate will roll or slide along the edge 48 until they reach the eyelet-guide 49, which is constructed and arranged to direct them onto the raceway. As each edge 48 of the picker plate reaches a position in line with the lower side of the raceway, the one-toothed gear 271 becomes disengaged from the gear 253, which results in a period of rest in the turning movement of the plate sufficient to permit the eyelets to slide therefrom onto and down the raceway to the spring-actuated finger 51 at the end thereof, which holds the eyelets back until they are picked off of the raceway by the spindle of the eyelet set. To prevent the eyelets from becoming jammed at the raceway entrance, a yielding spring-actuated member 52 may be located at this point, as shown in Fig. 11.

Referring to Fig. 1, the eyelet set 258 is provided with a cap 265, having therein the usual setting depression, and through which projects the spring-pressed eyelet spindle 264. The eyelet set has a forked portion to embrace the upper end of its plunger 120, to which it is pivotally connected at 260, and an angularly disposed arm or extension carrying a roll 261, which fits in and is guided by a cam slot 262, having a vertical portion and an inclined portion as shown, in a plate 263 secured to the machine frame.

The eyelet raceway 50 and hopper 40 are caused to swing on the pivotal bearings heretofore described by a lever 53, Fig. 2, having a forked end which engages a projection 54 on the raceway, the lever being shown as pivotally mounted on a pin 55, carried by a collar 56, which is clamped or otherwise secured to a pin 57, or other suitable support carried by the frame of the machine, the lever deriving its motion from a cam way or groove 4 in a cam which is fast on the shaft 1, see Fig. 5. The described movements imparted to the eyelet raceway cause it first to be moved toward the eyelet set so that its end portion passes down and over upon the spindle 264 thereof, when the set occupies the inclined position as shown in Fig. 1, just prior to the operation of setting the eyelets in the stock, which impales on the spindle the lowest eyelet in the raceway. That side of the raceway which is uppermost when the parts occupy this position is cut away for a short distance from the lower end of the raceway, as shown in Fig. 2, on a line substantially parallel with the plane in which the eyelet set swings upward when it moves about the center 260, to permit the set to remove the lowest eyelet from the end portion of the raceway, it being understood that said eyelet rests against a suitable stop which retains it until so removed. Following the described movement of the raceway the eyelet plunger rises, during which movement the action of the cam 262 on the roller 261 turns the eyelet set from an inclined to a vertical position, thereby withdrawing the eyelet on the spin-

dle from the lower end of the raceway, and the continued rise of the set carries the eyelet to the point where it enters the hole made in the stock by the punch, and is clenched by the anvil coöperating with the eyelet set. During the last portion of the upward movement of the eyelet set the raceway is swung in a direction contrary to that above described, in order to be in a position to repeat the operation.

The lacing hook-containing hooper 65 is, as shown in Fig. 10, supported by the frame of the machine in a position to the right of the center thereof, and an extension of the frame serves as the bottom or back of the hopper. The rotatable shaft 254 carries the picker plate 66 within the hopper, whose construction and mode of operation may be substantially the same as the picker plate 20 45. The numeral 259 indicates the lacing hook raceway which conducts the hooks from the hopper 65 to the hook setting device 80. A hook separator 67, shown in Figs. 4, 16, and 18, is supported for oscillating movements in bearings 68 carried by a bracket secured to the raceway 259, and is connected, through a lever 69 and links 70, with a cam lever 71 pivoted to brackets on the machine frame. The cam lever 71, as 25 30 shown in Fig. 4, is provided with a cam-way within which plays a pin or roll 72, carried by the hook set plunger 73, the cam-way being so shaped that as the plunger descends after setting a hook, the pin will 35 impart an oscillating movement to the separator to release a hook and permit it to slide down the raceway under an arm 74 (see Fig. 18), the separator at the same time moving in front of the next succeeding hook 40 to prevent its release.

The arm 74 is provided with a supporting stem 76, preferably integral therewith, which is journaled for axial turning movements in the front plate 75 of the machine 45 frame, and carries at its lower end a disk 77 whose lower face is provided with a cam-rise or enlargement. This disk is sustained by a pin 78, secured to the frame, against the thrust of a spiral spring 79, which may 50 surround the stem 76. As the arm 74 is moved in a backward direction, by mechanism to be hereinafter described, the cam face on the disk 77 acting on the pin 78 will cause the arm to rise and pass over the hook 55 which has just been released by the separator 67, such hook being then in the position indicated by the numeral 104 in Fig. 13, and permit it to slide under the arm. The hook moves under the force of gravity 60 sufficiently far beyond the arm 74 to reach a position on the raceway where it will be caught by the arm in its next forward and downward movement, and be swept on to the hook-supporting plate of the hook set 65 80, which is provided with a vertical wall

81 to arrest the movement of the hook and properly locate it thereon.

The hook set 80 has a pivotal connection 82 with its plunger 73, and the plunger is formed with a recess which contains 70 a spring-actuated bolt 95 to act upon the end of the hook set with a normal tendency to hold it in vertical alinement with its plunger. The plunger and set are guided for vertical movements toward and from 75 hook-receiving and hook-setting positions, in grooves which are formed partly in projections 83, 84 and 85 on the front plate of the machine frame, and partly in caps 86, 87 and 88 which cover and are secured 80 to said projections. The upper cap, 86, also serves as a sustaining member for the work support, which comprises the lower and upper plates, 89, 90.

The upper plate 90 of the work support is 85 provided with a transverse groove or way, as shown in Figs. 15 and 18, in which a slide 91 plays, the slide having guiding flanges to rest upon shoulders formed along the sides of the groove, and having also in its front 90 wall a recess 93' whose sides converge upwardly and inwardly. A pin 93, attached to the slide, extends rearwardly through a bore in the plate 90 where it terminates in a head, the pin being surrounded by a spiral spring 95 92 which is confined between the plate and slide and acts to yieldingly press the slide forward until checked by the action of the head of the pin against the rear wall of the plate. By this construction, when the hook 100 set rises from its hook-receiving position at the end of the raceway, as shown in Figs. 4, 13, and 14, to its hook-setting position, as shown in Fig. 18, the hook carried on the plate of the set engages the recess 93' in the 105 slide 91, which yields slightly, and acts to properly align the hook with reference to the hook set anvil, and to hold it accurately in position while it enters the punched hole in the stock, and until the completion of the 110 setting operation.

Referring to Figs. 3, 5, 7, 13 and 14, the numeral 97 indicates the hook-releasing lever which is pivotally supported on a stud 98, fast to the frame of the machine, and has secured to its upper end a finger 96, the lever carrying a cam roll to enter a cam way 9 in a cam disk fast on the shaft 1, whereby it may be oscillated to cause the finger 96 to tilt the hook-set outwardly and disengage it from the hook after the setting operation, as will be more fully explained hereinafter. In the upper part of the lever 97 a pin 99 is pivotally mounted, and, as shown, the pin has a forked end whose two members are apertured to receive a swiveled stud 260 which is provided with a transverse aperture to receive the stem of a link 100, sliding freely therein. The stem of link 100 is surrounded by a spiral spring 103 which is confined be- 130

tween a washer at one end of the stem and the stud 260, and the opposite end of the link is forked, and the members thereof apertured to receive a pin 102, which passes therethrough and through an eye in a stud 101, which is received in said forked end, the stem of the stud 101 fitting an opening through a sleeve or extension of the arm 74. The members of the forked end of the link 10 are sufficiently spaced from the eye of the stud 101 to permit the required amount of lost motion necessitated by the rising and falling movements of the arm.

Referring to the parts just described, immediately after a hook has been set the arm 97 moves forward, causing the finger 96 to engage the set 80 and tilt it, thereby disengaging the set from the hook, the arm in such operation imparting, through the connections described, an axial turning movement to the stem 76, which, through the action of the cam disk and pin, is lifted as it turns and carries the arm 74 upwardly and back to the position shown in Fig. 13. The plunger 73 and hook set 80 then move downwardly until the set reaches a position opposite the end of the raceway (Fig. 13), the cap 86 being cut away, as shown in Fig. 1 to permit the set to clear the end of the finger 96, thereby, through the action of the pin 72 on the cam lever 71, causing the separator to release another hook, during which movement the lever 97 remains forward and the finger 74 occupies a raised position above the raceway, permitting the released hook to slide beneath it, as shown at 104, Fig. 13. The lever 97 then moves to its rearward position, causing the arm 74 to move forwardly and downwardly to sweep the hook on to the hook-supporting plate of the set. In the event of there being any obstruction offered to the movement of the arm during this operation, as, for instance, if a hook should reach its final position of rest against the wall 81 of the set before the lever had completed its backward movement, the spring 103 would yield and permit the lever to complete its backward movement. The set then rises from its position opposite the end of the raceway and carries the hook into engagement with the slide 91, which serves to align and properly position the hook as its barrel rises through the opening in the work support and enters the aperture made by the punch in the stock, and thereafter the anvil engages the hook and co-operates with the set to clench it in the stock.

Referring to Fig. 1, the numeral 73 indicates the hook-set plunger which is arranged to co-operate with the hook anvil plunger 122, and 120 indicates the eyelet set plunger which is arranged to co-operate with the eyelet anvil plunger 121, said plungers being guided in grooves or ways formed in the frame of the machine in which they are

retained by caps 86, 87, 88, 123 and 124. In order that the eyelet set and anvil plungers may be reciprocated simultaneously in opposite directions to set eyelets, or the hook-set and anvil plungers may be so operated to set hooks, I have, in the present embodiment of the invention, provided two driving blocks, 125 and 126, the former of which is connected through a link 154, bell-crank lever 152 and link 155, and the latter through a link 151, respectively, with the opposite ends of a cam lever 148, pivoted to a stub-shaft 150 in the frame, and deriving its motion from the cam way 6 in a cam disk fast to the shaft 1. The driving blocks are, through the mechanism described, simultaneously reciprocated in opposite directions, and when connected to the plungers carrying the eyelet set and its anvil, or to the plungers carrying the hook-set and its anvil, serve to impart to these parts the necessary movements to cause them to set the fasteners in the stock.

The driving blocks are provided with vertical grooves to receive, and slidably engage, the plungers, to which they are confined by the caps 127 and 128, respectively. The caps 123, 127, 128 and 88, and the adjacent portions of the machine frame and of the driving blocks to which these caps are secured, are provided with transverse grooves to receive, respectively, the locking keys 129, 130, 131 and 132, whose construction, and mode of operation in the several positions they assume in locking the plungers to the driving blocks and to the frame of the machine, are illustrated in Figs. 19 to 22, inclusive. The keys are formed, as shown, with cut out portions or recesses whose edges are designed to engage with notches formed in the several plungers, and are so located that when the keys are moved simultaneously in one direction the plungers carrying the eyelet set and eyelet set anvil are locked to the frame, while the plungers carrying the hook set and hook set anvil are locked to the driving blocks, and when they are moved simultaneously in the opposite direction the plungers carrying the eyelet set and eyelet set anvil are locked to the driving blocks while the plungers carrying the hook set and hook set anvil are locked to the frame. Fig. 19 shows the position of the keys 130 and 131 in locking the plungers 121 and 120 to the driving blocks 125 and 126, and Fig. 20 shows the position of the keys 129 and 132 in locking the plungers 73 and 122 to the frame, following a simultaneous movement of the keys toward the right. Fig. 21 shows the position of the keys 130 and 131 in locking the plungers 73 and 122 to the driving blocks 125 and 126, and Fig. 22 shows the position of the keys 129 and 132 in locking the plungers 121 and 120 to the frame, fol-

lowing a simultaneous movement of the keys toward the left. The keys are formed with openings 267, at or near their ends, to receive pins, 133 and 134, the former of which carries arms 134' and 135, fast to a rock-shaft 138 journaled in the upper part of the frame, and the latter carries arms 136 and 137 fast to a rock-shaft 139, journaled in the lower part of the frame, as shown in Figs. 1 and 23, the keys 130 and 131 being capable of sliding freely on these pins. The pin 133 is connected by a link 140 to an arm 142, and the pin 134 by a link 141 to one arm of a bell-crank lever 143, which arm and bell-crank lever are fastened to a rock-shaft 144 journaled in the frame of the machine. The opposite arm 145 of the bell-crank lever is connected through a link 147 with the cam lever 146 (Fig. 23) which carries a roll and is held by one of a series of springs 248 in engagement with the periphery of one of the pattern cams *f*, on the shaft 8. By this arrangement, the pattern cams *f*, which are variously designed, will control, automatically, the positions of the keys and thereby determine the time when the eyelet setting devices are rendered operative and the hook setting devices are rendered inoperative, and vice versa. The operator may shift the shaft 8 through the lever 15, and move any one of these cams to a position where it will control the lever 146, in accordance with its patterned surface, to cause the machine to set a given number of eyelets and then set a given number of lacing hooks, and the machine will continue to alternately set the numbers of these fasteners thus predetermined by the shape of the cam, without any further attention on the part of the operator. Should, however, the operator desire to change the number of the fasteners to be set by the machine, the shaft 8 may be shifted to locate any other one of the cams *f* opposite the lever 146, and the number of eyelets and lacing hooks that the machine will set will then be governed by the patterned surface of that particular cam.

Referring to Figs. 3, 9, 9^a and 9^b, which represent the punching mechanism, the numeral 159 indicates a hollow stud which is rigidly secured to the frame of the machine in any suitable manner, as by a nut, as shown, and 166 and 166^a the two members of a punch carrier which surround and are free to rotate on the stud. The lower member of the carrier is extended toward the front of the machine and provided with an anvil 174, for the punches, and the upper member has rigid therewith an arm 191. Both members of the carrier are formed with alined openings having bushings to afford bearings for a plunger 164, which may slide and turn freely therein, the plunger also passing through an opening in the

punch holder 162, to which it is rigidly secured by a pin 165. Two punches, 160 and 161, the former being of a size of and adapted to make holes in stock suitable for one kind of fasteners, as eyelets, and the latter of a size to make holes in stock suitable for another kind of fasteners, as lacing hooks, are clamped, respectively, to two arms extending from the holder, by screws 163, or equivalent means. The plunger and punches carried thereby are caused to reciprocate through a link 172, which is connected by a ball and socket joint with the plunger, and pivotally with a lever 169, fulcrumed at 170 to the carrier, a rod 171 having one end in rotative engagement with a sleeve pivoted to said lever and its opposite end pivotally connected with a cam lever 167, fulcrumed on a shaft 168, said lever carrying a cam roll which enters a cam way or groove 5 in a cam disk fast on the shaft 1.

Surrounding the upper member 166 of the carrier, and turning freely thereon, is a collar carrying a segmental gear 173, which meshes with a segmental gear 345, formed on the rear part of the punch holder 162, and secured to this collar by a pin 175 is another collar having thereon a beveled segmental gear 176, which meshes with and is driven by a beveled segmental gear 177, carried by a bell-crank lever 277, which has a sleeved extension to fit and turn freely on a stem 178. The stem 178 is fast to or integral with the upper member 166 of the carrier, and the sleeve of the gear 177 is confined to the stem by a screw and washer 179, as shown. Extending from this sleeve is an arm carrying a second sleeve within which is pivoted the stem 278 of a forked member 180 whose arms embrace, and slide freely along, a sleeve 181, rectangular in cross section, and which is pivotally mounted on a pin 182 held between the forked ends of one arm of a lever 183. The lever 183 is fulcrumed on a stud shaft 184, secured to the frame, and derives its motion from one of the pattern cams *b*, through a cam lever 185, to which its other arms is connected by a link 186.

When the punch carrier is moved about the hollow stud 159, through the feeding mechanism, which imparts an angular motion to the punches, to feed the stock, the position of the punches relatively to the anvil 174 remains unchanged as long as the vertical position of the sleeve 181 is not varied, and the forked member 180, during such movements, slides along the sleeve; when, however, that point in the cycle of operations of the machine is reached where the eyelet punch is to be rendered operative, and the hook punch is to be rendered inoperative, or vice versa, one of the cams *b* will actuate the cam lever 185, and, through 130

the connections described, the sleeve 181 and forked member 182 will be raised or lowered, and the punch holder turned, to the right or to the left, to locate the desired one of the punches in proper alignment with the anvil 174. In Fig. 9 of the drawings the punches are shown in intermediate position, neither of them being in operative relation with the anvil. While the mechanism described will serve to effect an approximately correct location of either punch with respect to the anvil, in order to insure exact alignment two upwardly projecting dowel pins 187 and 188, having rounded or tapered ends, are fixed to the lower member 166^a of the punch carrier, and the punch holder has two holes, 189 and 190 therein, which are so located that one of said holes will be entered by a dowel pin as the holder descends, and thereby accurately center the punch.

The mechanism for imparting the feeding movements to either one of the punches while it occupies the punched hole in the stock, is illustrated in Figs. 5, 7, 23, 24 and 25. The arm 191 of the punch carrier is connected, through a link 192, with a pin 195, eccentrically mounted at the end of a shaft 193, which is journaled in a feed slide 194. When the shaft 193 is turned to move the eccentric pin 195 toward the front of the machine, as shown in Fig. 7, and the feeding movements are imparted to the punch by the slide 194, through connections to be described, the punch will be located, at the termination of such movements, under the eyelet set. If, however, the shaft is turned reversely to carry the pin to a rearward position, the punch will be located, at the termination of the feeding movements, under the hook set. These changes in the location of the punch at the final point in the forward stroke of the feed slide are effected automatically, and through mechanism which is controlled by one of the pattern cams *d*, it being understood that the parts are so timed that the feeding movements of the punch will be made to terminate under the setting device which is then in operation. The shaft 193 carries a pinion 270 which meshes with a rack 196 having a bearing in the feed slide 194. A squared block enters a slot in the rear part of the rack to which it is pivotally connected by a pin 200, and a bell-crank lever 197, having its fulcrum at 198, on a link 199, has its upper end forked to embrace the squared block to which it is pivotally connected, and its lower end connected, through a link 201, with a cam lever 202, carrying a roll for cooperation with one of the pattern cams *d*. The feed slide 194 is pivotally supported on two links, the forward one of which, 203, rocks upon a stud shaft 204 fast to the frame, and the rear one, 199, rocks upon a stud

shaft 203, also fast to the frame. The link 205 is slotted and a cam lever 209 pivoted at one end to a stud shaft 211 fast to the frame, and carrying at its opposite end a roll to enter a cam way 7 in a cam disk on the shaft 1, 70 is similarly slotted. A pin 206, upon which are pivotally mounted two rectangular-shaped blocks, is located in the slots in the links, along which the blocks have a sliding engagement. The outer end of this pin is 75 extended, and connected thereto by a link 207, is a lever 208, fulcrumed to the shaft 247, said lever having one arm rearwardly extended and provided with a roll to coöperate with one of the pattern cams *e*, and its 80 other arm forwardly extended to form a handle 214, as shown, and passing through a slot in the front of the casing where it is in convenient position to be grasped by the operator, as shown in Fig. 1.

The extent of the angular motion which the cam way 7 imparts to the lever 209 is invariable, but the amount of such motion which is transmitted to the feed slide through the pin 206 and link 205 is made variable by the adjustment of the pin along the slots in the lever 209 and link 205. By this means, the extent of the feeding movements imparted to the punches by the described connections may be controlled, in order to 95 vary the spaces between the fasteners as they are set in the stock. It is sometimes found to be desirable to set the eyelets a different distance apart than the lacing hooks, and, for different kinds of work, to set either or both of these fasteners at varying distances from each other. To this end, the pattern cams *e* may be so designed as to govern the spacings desired for a number of 100 different kinds of work, and when one of these cams is located opposite the lever 208, the spacing will be automatically controlled thereby. The spacings may be controlled manually, if desired, independently of the pattern cams, through the handle extension 105 214 of the lever 208, the limits of whose movements in opposite directions are shown as being capable of adjustment by two pins 213, each to be located in any one of a series 110 of holes formed in a bracket 212, secured to the frame.

Referring to Figs. 7, 18, 24 and 25, the edge gage 215 is shown as formed of two parts, which may be connected by a screw and dowel pins, as indicated at 216, the gage 120 being controllable as to its position in order to determine the distance that the fasteners will be set from the edge of the stock, by one of the pattern cams *e*, acting on a cam lever 217, which is connected with the edge 125 gage. The pattern cams may be designed to vary the distance from the edge of the stock at which the fasteners are to be set in any manner desired, so that the eyelets will be set at one distance from said edge, and the 130

lacing hooks at a different distance therefrom, or so that both kinds of fasteners will be set at the same distance from said edge. Preferably, the edge gage should occupy a 5 position immediately to the rear of the setting device which is in operation, and as the eyelet set and the hook set are located side by side, it is desirable to move the gage laterally to its proper position back of each 10 set prior to the beginning of the operation of the set. To this end, a carrying plate 218 is provided, which is connected at one end by an eccentric pin 219 and crank arm 220, with the shaft 193, and is guided near its opposite 15 end between two pins, 221 and 222, which are fast to the frame of the machine. The carrying plate supports the edge gage, and is provided with two spaced pins 223 and 224, between which the gage is confined 20 against lateral movements, but is free to slide longitudinally. By this construction, the partial rotation imparted to the shaft 193 to alter the terminal point in the feeding movements of the punch will simultaneously 25 move the carrying plate, and through such plate the edge gage, to the right or to the left, to thereby locate the gage to the rear of the setting device then in operation.

30 The presser-foot 225, as shown in Fig. 2, is preferably curved and may be secured by a screw 227, or equivalent means, to a pin 226 which is guided for reciprocating movements in openings formed in the frame of the machine. A spring 229 surrounds the pin 226, and is confined between a projecting part of the frame and the top of the presser-foot with a normal tendency to force the presser-foot toward the work support. The 35 presser-foot is guided by a pin 228 which is fast to the frame and enters a hole in the presser-foot. The lower end of the pin 226 is provided with a foot 230 which is held by the spring 229 in engagement with the surface of a cam, fast on the shaft 1, and having an elevation 3 which is so located as to raise the presser-foot from the work during the feeding movements of the punch.

40 Referring to Figs. 5 and 6, the clutch is shown as comprising the member 231 having oppositely beveled surfaces, and formed with an aperture of square, or similar cross section, to fit a square portion of the shaft 1, whereby it may slide thereon, but is constrained to rotate with the shaft. An extension of this clutch member is grooved to receive two inwardly extending projections from the forked end of a clutch-actuating lever 236, which is pivoted at 237 to a bracket secured to the frame of the machine. The 45 loose pulley 232 is rotatively mounted upon a sleeve 233 to which it is confined against longitudinal movement between a collar at 50 the inner end of the sleeve and a washer,

or similar locking device, 234, held fast against the outer end of the sleeve by the head of a screw-bolt 235, having a shank to enter a threaded hole in the end of shaft 1. The sleeve 233 is provided at its outer portion with an internal screw-thread which engages an external screw thread on the end of the shaft 1, whereby the loose pulley, together with the sleeve which constitutes its bearing, may be removed bodily from the shaft, or adjusted longitudinally thereon. The sleeve is practically the same length as the hub of the pulley, and when the washer 234 is clamped against the end of the sleeve by the screw-bolt the sleeve will be locked 70 securely to the driving shaft and will be prevented from rotating relatively thereto. As shown in Fig. 5, there is a space between the extremity of the driving shaft and the washer which is sufficient to permit a certain 75 amount of adjustment of the sleeve and pulley toward the clutch member.

The oppositely disposed beveled or inclined surfaces of the clutch member cooperate, respectively, with like surfaces on the inner face of the loose pulley, and on the frame of the machine. When the clutch member is moved in one direction it engages with the loose pulley and the power conveyed by the usual belt to the pulley is then 80 applied to the shaft 1; and when the clutch member is moved in the opposite direction, it disengages from the loose pulley and engages with the beveled surface on the machine frame, which acts as a friction brake 85 and stops the rotation of the shaft. A spring 238, which is confined between a fixed part of the frame and an arm of the lever 236, acts to normally move the clutch member in a direction to engage the loose pulley. 90 A cam lever 239 is pivotally supported from a link 267, which is pivoted to a bracket fast to the frame and carries two oppositely extending arms 269, which bear against two set screws 273, whereby the lower end of the 95 link, and the lever carried thereby, may be adjusted laterally with respect to the face of a cam 2, formed on a cam-disk fast on the shaft 1, and at an intermediate point the lever carries a roll which normally engages 100 the face of this cam. A trip 240 is pivotally connected at one end with the lever 239, and at its opposite end is curved to correspond with the surface of a roll 242, journaled in the end of the clutch-actuating lever 236. 105 The trip has attached to it at an intermediate point a treadle rod, or equivalent connection 241, in order that it may be actuated manually to disengage its free end from the roll 242, and a spring (not shown) 110 acts upon the release of the treadle to move the rod 241 reversely to cause the trip to come into engagement with the roll. With the parts of the clutch mechanism as thus far described, it will be obvious that if the 115

operator steps on the treadle connected with the rod 241 the end of the trip 240 will be withdrawn from engagement with the roll 242, and the trip will assume the position 5 shown in dotted lines, Fig. 5, thereby permitting the spring 238 to act, and, through the lever 236, to force the clutch member into engagement with the loose pulley and cause the shaft 1 to rotate; and if the treadle is 10 released the trip will again move into engagement with the roll, so that when the shaft has made one complete rotation the cam 2 will reversely actuate the clutch member to set the friction brake and stop the rotation of the shaft, unless otherwise prevented.

The number of teeth in the several gears constituting the train connecting the shaft 1 with the shaft 8 are so proportioned to each 20 other that the shaft 1 rotates a plurality of times for each single rotation imparted to the shaft 8, and in order to complete a cycle of operations of the machine, during which a predetermined number of eyelets and a 25 predetermined number of lacing hooks are set in the stock, it is necessary that means be provided to prevent the clutch from being actuated when the treadle is released until the shaft 1 has made the required number 30 of rotations to set the desired number of fasteners. To this end, a cam lever 243 is pivoted to the shaft 247, and carries upon one arm a roll to be held by a spring 248 in engagement with the surface of any one of 35 the three pattern cams *a*, and has pivotally connected with its other arm, a latch 244, which is arranged above the trip 240. When the trip is moved out of engagement with the roll 242 to start the machine, and the shaft 40 8 begins to rotate, if the treadle is released the pattern cam then in operative relation with the lever 243 will effect a depression of the latch and cause its end to engage a shoulder on the trip and prevent the trip 45 from reengaging the roll 242 until the pattern cam reaches a point where it causes the lever 243 to raise the latch and permit such action. The cams *a* may be of different designs in order to provide for stopping 50 the machine any number of times during a cycle of operations, as may be desired, according to the character of the work. If, for instance, the machine was adjusted for 55 setting automatically a predetermined number of eyelets and a predetermined number of lacing hooks, it would be desirable to have the cam *a* which was in operation so designed as to cause the machine to stop twice, that is, once immediately after all of the 60 first one of these kinds of fasteners had been set, and again after the last fastener had been set in the stock.

While the cams *a* are, in practice, so designed as to permit the clutch mechanism to

bring the machine to a stop automatically at 65 such times as may be best suited to most conditions of work under which the machine may operate, it is sometimes desirable to stop the machine before the cam *a* reaches the point to raise the latch 244. For this 70 purpose, a lever 245, which is pivoted to a stud 246 fast to the machine frame, is arranged to extend along the side of the latch and to project through an opening in the 75 front of the frame, within convenient reach of the operator. To stop the machine, the operator moves this lever to one side so as to swing the latch off from the shoulder on the trip, thereby permitting the trip to rise and its end to engage the roll 242, so that the cam 2 may, through the connections described, effect a shifting of the clutch member to set the brake and stop the machine. The lever 245 is then returned to its original 80 position, and the latch swings back to lie vertically, and is thereby properly located to act again upon the trip, when the same is depressed through the treadle, and to hold it away from the roll 242 until it is released through the automatic action of the pattern cam.

While the machine as herein illustrated is provided with setting devices, raceways, and hoppers that are so constructed as to set lacing hooks and eyelets in stock, it is to be 95 understood that the invention in its broadest aspect contemplates the setting of other kinds of fasteners, as, for instance, two different sizes or styles of eyelets, and where the term "fastener" is used in the claims, without further qualification, it is intended to refer to eyelets, lacing hooks, studs, rivets, or any similar devices which may be secured in the uppers of boots or shoes.

If desired, the several cam levers, which 105 are normally maintained in operative relation to the pattern cams by the springs 248, may be provided with extensions 300, having connections 301, or the like, with treadles or other suitable operating devices, as shown 110 in Fig. 3. By this means, the operator may lift any of the cam levers from their cams, and thereby render such cams ineffective to control the mechanisms connected therewith while the remaining cams operate to perform 115 their usual functions.

Having thus described my invention, what I claim as new and desire to secure by Letters Patent of the United States is:—

1. In a machine of the class described, the 120 combination with automatic means for successively setting two kinds of shoe upper fasteners along the edge of an upper, of mechanism for variably determining the number of such fasteners.

2. In a machine of the class described, the 125 combination with automatic means for successively setting two kinds of shoe upper

- fasteners along the edge of an upper, of mechanism for variably determining the number of each kind of said fasteners. 5
3. In a machine of the class described, the combination with mechanism constructed and arranged to automatically control the setting of a predetermined number of a plurality of kinds of shoe upper fasteners along the edge of an upper, of means under the control of the operator to vary the number of such fasteners to be set. 10
4. In a machine of the class described, the combination with eyelet setting means, hook setting means, and actuating devices therefor, of mechanism acting automatically to cause a plurality of operations of first one and then the other of said means to set eyelets and hooks in stock in predetermined numbers. 15
5. In a machine of the class described, the combination with eyelet setting means, hook setting means, and actuating devices therefor, of mechanism acting automatically to cause a plurality of operations of first one and then the other of said means to set eyelets and hooks in stock in predetermined numbers, and means under manual control to vary the number of eyelets and hooks to be set. 20
6. In a machine of the class described, the combination with eyelet setting means, hook setting means, and actuating devices therefor, of mechanism acting automatically to cause one of said means to operate a predetermined number of times, and to then stop the machine, manually controllable devices for restarting the machine, and means to thereafter cause the other of said means to operate a predetermined number of times. 25
7. In a machine of the class described, the combination with means for successively setting a plurality of eyelets and a plurality of hooks in stock, of mechanism constructed and arranged to stop the machine automatically after a predetermined number of either kind of fasteners have been set. 30
8. In a machine of the class described, the combination with means for successively setting eyelets and hooks in stock, of automatic mechanism constructed and arranged to stop the machine after a predetermined number of either kind of fasteners have been set, said mechanism being under the control of the operator, whereby the machine may be stopped at any point desired independently of the automatic mechanism. 35
9. In a machine of the class described, eyelet setting devices and hook setting devices, actuating members common to said devices, and automatic mechanism to operatively connect the eyelet setting devices to said members for a predetermined number of operations, and thereafter to connect the hook setting devices to said members for a predetermined number of operations. 40
10. In a machine of the class described, eyelet setting devices and hook setting devices, actuating members common to said devices and arranged to be connected therewith, and means governed automatically and constructed to connect the eyelet setting devices with said members and the hook setting devices with the machine frame, and thereafter to connect the hook setting devices with said members and the eyelet setting devices with the machine frame. 45
11. In a machine of the class described, the combination with eyelet setting devices and hook setting devices, each of said devices comprising a set and an anvil supported for reciprocating movements in opposite directions to clench fasteners in stock, of common actuating members therefor, and mechanism acting automatically to connect the eyelet setting devices to said members for a predetermined number of operations, and thereafter to connect the hook setting devices to said members for a predetermined number of operations. 50
12. In a machine of the class described, the combination of eyelet setting devices and hook setting devices, pairs of oppositely movable alined plungers carrying said devices, and arranged side by side, driving blocks having sliding engagement with said plungers, devices for simultaneously locking the eyelet setting plungers to the driving blocks and the hook setting plungers to the frame of the machine, and vice versa, means for actuating the driving blocks, and automatic mechanism to control the operation of the locking devices. 55
13. In a machine of the class described, the combination of eyelet setting devices and hook setting devices, pairs of oppositely movable, alined plungers, carrying said devices and arranged side by side, driving blocks having sliding engagement with said plungers, devices for simultaneously locking the eyelet setting plungers to the driving blocks and the hook setting plungers to the frame of the machine, and vice versa, means for actuating the driving blocks, and mechanism acting automatically to cause the locking devices to lock the eyelet setting plungers to the driving blocks for a predetermined number of operations, and thereafter to lock the hook setting plungers to said blocks for a predetermined number of operations. 60
14. In a machine of the class described, means for setting fasteners in stock, actuating mechanism therefor including a power shaft, a second shaft driven from said power shaft and carrying pattern mechanism, means for adjusting said mechanism, and devices controlled by said pattern mechanism to stop the rotation of the power shaft after a predetermined number of fasteners have been set. 65

15. In a machine of the class described, means for setting fasteners in stock, actuating mechanism therefor including a power shaft, a second shaft driven from said power shaft and carrying pattern mechanism, devices controlled by said pattern mechanism to stop the rotation of the power shaft after a predetermined number of fasteners have been set, and means under the control of the operator to determine the number of fasteners set through the action of the pattern mechanism.

16. In a machine of the class described, means for setting fasteners in stock, actuating mechanism therefor including a power shaft, a pattern cam shaft driven from said power shaft and supported for longitudinal as well as rotative movements, a plurality of pattern cams fast on said shaft and having variously designed surfaces, mechanism, including a member to be actuated by any one of said cams, constructed and arranged to stop the rotation of the power shaft after a predetermined number of fasteners have been set, and means under the control of the operator to shift the pattern cam shaft in order to locate any one of the pattern cams in operative relation with said member.

17. In a machine of the class described, the combination of devices for setting eyelets and devices for setting lacing hooks in stock, actuating mechanism therefor including a power shaft, a second shaft driven from said power shaft and carrying pattern mechanism, and devices controlled by said pattern mechanism to connect the actuating mechanism with one of the fastener setting devices for a predetermined number of operations, and thereafter to connect the actuating mechanism with the other fastener setting device for a predetermined number of operations.

18. In a machine of the class described, the combination of a device for setting eyelets and a device for setting lacing hooks in stock, actuating mechanism therefor including a power shaft, a second shaft driven from said power shaft and carrying pattern mechanism, devices controlled by said pattern mechanism to connect the actuating mechanism with one of said setting devices for a predetermined number of operations and thereafter to connect the actuating mechanism with the other of said setting devices for a predetermined number of operations, and means under the control of the operator to vary the action of the pattern mechanism.

19. In a machine of the class described, the combination of devices for setting eyelets and devices for setting lacing hooks in stock, actuating mechanism therefor including a power shaft, a pattern cam shaft driven from said power shaft and supported for longitudinal and rotative movements, a

plurality of pattern cams fast on said shaft and having variously designed surfaces, mechanism, including a member to be actuated by any one of said cams, constructed and arranged to cause the devices for setting eyelets and the devices for setting hooks to operate, consecutively, for a predetermined number of times, and means under the control of the operator to shift the pattern cam shaft in order to locate any one of the pattern cams in operative relation with said member.

20. In a machine of the class described, devices for setting fasteners, actuating mechanism therefor including a power shaft, a pattern cam shaft driven from said power shaft and supported for longitudinal and rotative movements, pattern cams fast on said shaft. mechanism arranged to be actuated by said cams to control the setting of fasteners, and means under the control of the operator for shifting the pattern cam shaft longitudinally to bring different cams into operative relation with said mechanism.

21. In a machine of the class described, devices for setting fasteners, actuating mechanism therefor including a power shaft, a pattern cam shaft driven from said power shaft and supported for longitudinal and rotative movements, pattern cams fast on said shaft and all constructed with a point in their peripheries which is the same distance from their center of rotation, said points being in line, cam levers in engagement with said cams and connected with devices to control the setting of fasteners, a series of spaced disks secured to said shaft and having peripheral openings arranged in line, a projection fast to the machine frame and adapted to enter the spaces between said disks, or to pass through said peripheral openings, and means to effect a longitudinal movement of the pattern cam shaft.

22. In a machine of the class described, devices for setting fasteners, actuating mechanism therefor including a power shaft, a shaft supported for longitudinal and rotative movements and having fast thereon a plurality of series of pattern cams to effect different operations in the setting mechanism, a plurality of gears loose on the pattern cam shaft and having different numbers of teeth thereon, said gears meshing with a similar number of gears forming part of a train which connects the pattern cam shaft with the power shaft, means on the pattern cam shaft to effect its engagement with any one of the gears thereon when the shaft is shifted longitudinally, and means for shifting said shaft.

23. In a machine of the class described, devices for setting fasteners, actuating mechanism therefor including a power shaft, a gear arranged to slide on said shaft but constrained to rotate therewith, a shaft

supported for rotative movements and having pattern cams fast thereon constructed and arranged to effect different operations in the setting mechanism, a train of gears connecting the gear on the power shaft with the pattern cam shaft, and manual means to rotate the pattern cam shaft.

24. In a machine of the class described, devices for setting fasteners, actuating mechanism therefor including a power shaft, a gear arranged to slide on said shaft but constrained to rotate therewith, a shaft supported for longitudinal and rotative movements and having pattern cams fast thereon constructed and arranged to effect different operations in the setting mechanism, a train of gears connecting the gear on the power shaft with the pattern cam shaft, means to prevent longitudinal movement of the pattern cam shaft except when it reaches a certain point in its rotation, a movable stop to arrest the rotation of the shaft when it arrives at said point, yielding means for rotating the shaft to cause a projection thereon to engage said stop, and manual means for rotating the shaft in a contrary direction.

25. In a machine of the class described, devices for setting fasteners in stock, actuating mechanism therefor including a power shaft having a driving pulley loose thereon, a clutch member to connect said shaft and pulley, means to cause engagement between said clutch member and pulley to effect rotation of the shaft, means carried by the shaft to cause disengagement of said parts to stop the rotation of the shaft, devices, acting automatically, to render the action of the last-named means ineffective until a predetermined number of fasteners have been set, and means under the control of the operator to vary the operation of said devices.

26. In a machine of the class described, devices for setting fasteners in stock, actuating mechanism therefor including a power shaft having thereon a loose pulley, a clutch member on said shaft and arranged for engagement with the loose pulley to effect rotation of the shaft, means on the power shaft to disengage said clutch member and loose pulley, and devices to render the action of the last named means ineffective until a predetermined number of fasteners have been set.

27. In a machine of the class described, devices for setting fasteners in stock, actuating mechanism therefor including a power shaft having thereon a loose pulley, a clutch member on said shaft and arranged for engagement with the loose pulley to effect rotation of the shaft, means to cause such engagement, a cam on the power shaft to disengage said clutch member and loose pulley, and devices to render the action of said cam

ineffective until a predetermined number of fasteners have been set.

28. In a machine of the class described, devices for setting fasteners in stock, actuating mechanism therefor including a power shaft having a driving pulley loose thereon, a brake, a clutch member arranged to connect the power shaft with the loose pulley or with the brake, a clutch-actuating lever, yielding means acting thereon to move said member into engagement with the loose pulley, a cam on the driving shaft to move said member into engagement with the brake, a lever to be actuated by said cam, a trip having one end pivotally connected with said lever and its opposite end arranged to be normally held in engagement with the free end of the clutch-actuating lever, and means under the control of the operator to disengage said trip.

29. In a machine of the class described, devices for setting fasteners in stock, actuating mechanism therefor including a power shaft having a driving pulley loose thereon, a brake, a clutch member arranged to connect the power shaft with the loose pulley or with the brake, a clutch-actuating lever, yielding means acting thereon to move said member into engagement with the loose pulley, a cam on the driving shaft to move said member into engagement with the brake, a lever to be actuated by said cam, a trip having one end pivotally connected with said lever and its opposite end arranged to be normally held in engagement with the free end of the clutch-actuating lever, means under the control of the operator to disengage said trip, and automatic means to prevent reengagement of said trip and clutch-actuating lever until a predetermined number of fasteners have been set.

30. In a machine of the class described, devices for setting fasteners in stock, actuating mechanism therefor including a power shaft having a driving pulley loose thereon, a brake, a clutch member arranged to connect the power shaft with the loose pulley or with the brake, a clutch-actuating lever, yielding means acting thereon to move said member into engagement with the loose pulley, a cam on the driving shaft to move said member into engagement with the brake, a lever to be actuated by said cam, a trip having one end pivotally connected with said lever and its opposite end arranged to be normally held in engagement with the free end of the clutch-actuating lever, means under the control of the operator to disengage said trip, a pattern cam, and a lever controlled thereby and carrying a pivoted latch to engage said trip and prevent it from reengaging the clutch-actuating lever until a predetermined number of fasteners have been set.

31. In a machine of the class described,

devices for setting fasteners in stock, actuating mechanism therefor including a power shaft having a driving pulley loose thereon, a brake, a clutch member arranged to connect the power shaft with the loose pulley or with the brake, a clutch-actuating lever, yielding means acting thereon to move said member into engagement with the loose pulley, a cam on the driving shaft to move said member into engagement with the brake, a lever to be actuated by said cam, a trip having one end pivotally connected with said lever and its opposite end arranged to be normally held in engagement with the free end of the clutch-actuating lever, means under the control of the operator to disengage said trip, a pattern cam, a lever controlled thereby and carrying a pivoted latch to engage said trip and prevent it from re-engaging the clutch-actuating lever until a predetermined number of fasteners have been set, and means under the control of the operator for moving said latch out of engagement with the trip to thereby permit the clutch actuating mechanism to act and stop the rotation of the power shaft independently of the operation of the pattern cam.

32. In a machine of the class described, the combination with eyelet setting devices and lacing hook setting devices, and means to render one of said devices operative and the other of said devices inoperative, and vice versa, of punches which are, respectively, appropriate for each of said devices, and mechanism acting automatically to render the eyelet punch effective when the eyelet setting devices are operative, and to render the lacing hook punch effective, when the lacing hook setting devices are operative.

33. In a machine of the class described, the combination with eyelet setting devices and lacing hook setting devices, and means to render one of said devices operative and the other of said devices inoperative, and vice versa, of punches which are, respectively, appropriate for each of said devices, an anvil for said punches, and mechanism to position the eyelet punch over the anvil when the eyelet setting devices are in operation and the lacing hook punch over the anvil when the lacing hook setting devices are in operation.

34. In a machine of the class described, the combination of two punches constructed to make holes in stock appropriate for different kinds of fasteners, an anvil for said punches, and automatic mechanism acting to position either of said punches over the anvil in accordance with the kind of fasteners to be set.

35. In a machine of the class described, the combination of two punches constructed to make holes in stock appropriate for different kinds of fasteners, an anvil for said

punches, automatic mechanism acting to position either of said punches over the anvil in accordance with the kind of fasteners to be set, means to actuate one of said punches to make a hole in the stock, and means to actuate said punch to feed the stock.

36. In a machine of the class described, the combination of a carrier, two punches movably mounted thereon, an anvil supported from said carrier, means to position either of the punches over the anvil, means to actuate one of said punches to make a hole in the stock, and means for actuating the carrier to cause said punch to feed the stock.

37. In a machine of the class described, the combination of an oscillatory carrier, an anvil supported thereby, two punches movably mounted on said carrier, means to position either of the punches over the anvil, means to actuate one of said punches to make a hole in the stock, and means for actuating the carrier to cause said punch to feed the stock.

38. In a machine of the class described, the combination of an oscillatory carrier, an anvil supported thereby, a plunger sustained for longitudinal and for axial turning movements in said carrier, two punches carried by said plunger, means to position either of the punches over the anvil, and means to reciprocate said plunger to cause the punch so positioned to make a hole in the stock.

39. In a machine of the class described, the combination of an oscillatory carrier, an anvil supported thereby, a plunger sustained for longitudinal and for axial turning movements in said carrier, a holder secured to said plunger and carrying two punches and a gear, a member rotatively supported on the carrier and having a gear to mesh with the gear on said holder, means for rotating said member to cause either of the punches to be positioned over the anvil, and means to reciprocate said plunger to cause the punch so positioned to make a hole in the stock.

40. In a machine of the class described, the combination of an oscillatory carrier, an anvil supported thereby, a plunger sustained for longitudinal and for axial turning movements in said carrier, a holder secured to said plunger and carrying two punches and a gear, a member rotatively supported on the carrier and having a gear to mesh with the gear on said holder, means for rotating said member to cause either of the punches to be positioned over the anvil, means to reciprocate said plunger to cause a punch to make a hole in the stock, and means for actuating the carrier to cause the punch to feed the stock.

41. In a machine of the class described, the combination of an oscillatory carrier, two punches movably mounted thereon, an anvil supported from said carrier, a lever fulcrumed to said carrier and having connection with said punches, mechanism, includ-

ing a bell-crank lever for actuating said lever to position either of said punches over the anvil, a connection permitting a relative sliding movement between said levers, and 5 means for actuating the carrier to cause a punch to feed the stock.

42. In a machine of the class described, the combination of an oscillatory carrier, an anvil supported thereby, a plunger sustained 10 for longitudinal and for axial turning movements in said carrier, a holder secured to said plunger and carrying two punches and a gear, a member rotatively supported on the carrier and having a gear to mesh with the 15 gear on said holder, a bell-crank lever fulcrumed on the carrier and having one arm in geared connection with said member and its other arm provided with a swiveled fork, a second bell-crank lever having one arm carrying 20 a member in sliding engagement with said fork, and its other arm connected with actuating mechanism for positioning the punches, and means for actuating the carrier to cause a punch to feed the stock.

43. In a machine of the class described, the combination of an oscillatory carrier, an anvil supported thereby, a plunger sustained 25 for longitudinal and for axial turning movements in said carrier, a holder secured to said plunger and carrying two punches and a gear, a member rotatively supported on the carrier and having a gear to mesh with the gear on said holder, a bell-crank lever fulcrumed on the carrier and 30 having one arm in geared connection with said member and its other arm provided with a swiveled fork, a second bell-crank lever having one arm carrying a member 35 in sliding engagement with said fork and its other arm connected with actuating 40 mechanism for positioning the punches, means for reciprocating the plunger to cause a punch to make a hole in the stock, and means for actuating the carrier to cause the 45 punch to feed the stock.

44. In a machine of the class described, a carrier, an anvil, a punch holder sustained by the carrier for lateral movements and for movements toward and from the anvil, 50 two punches carried by said punch holder, mechanism for actuating the punch holder to locate either punch in alinement with the anvil, and means to insure such alinement.

45. In a machine of the class described, a carrier, an anvil, a punch holder sustained 55 by the carrier for lateral movements and for movements toward and from the anvil, two punches carried by said punch holder, mechanism for actuating the punch holder to locate either punch in alinement with the anvil, and guiding devices located in part 60 on said carrier and in part on said holder to insure such alinement.

46. In a machine of the class described, 65 the combination of a tubular bearing, a car-

rier journaled thereon, a lever pivoted to said carrier, a plunger pivotally connected with one arm of said lever by means permitting axial turning movements, a punch holder secured to said plunger and carrying 70 two punches, an anvil, means for moving the punch holder to locate either punch over said anvil, mechanism for actuating said lever including a connection extending through said bearing, and means for actuating said carrier to cause a punch to feed the stock.

47. In a machine of the class described, the combination with setting devices for two kinds of fasteners, so located as to, respectively, occupy different lateral positions, of a punch, mechanism for rendering one fastener setting device operative and for rendering the other fastener setting device inoperative, and vice versa, and mechanism 80 for causing the punch to make a hole in the stock and to feed the stock the required distance for locating the punched hole in line with the setting device in operation.

48. In a machine of the class described, the combination with setting devices for eyelets and for lacing hooks, so located as to, respectively, occupy different lateral positions, of a punch, mechanism to render one 85 of said setting devices operative while the other of said devices is inoperative, means for causing the punch to make a hole in the stock and to feed the stock, and automatic mechanism to control the terminal point of such feeding movements constructed 90 and arranged to insure the location of the punched hole in line with the setting devices in operation.

49. In a machine of the class described, the combination of setting devices for two 95 kinds of fasteners, so located as to, respectively, occupy different lateral positions, mechanism for rendering one of said devices operative while the other of said devices is inoperative, a carrier, a punch supported 100 thereby, means for actuating said punch to make a hole in the stock, means for actuating said carrier to cause the punch to feed the stock, and automatic mechanism to control the terminal point of such feeding movements constructed 105 and arranged to insure the location of the punched hole in line with the setting devices in operation.

50. In a machine of the class described, the combination of a carrier, a punch sustained 110 thereby and arranged to feed the stock, a feed slide, actuating devices therefor, and an adjustable connection between the carrier and feed slide constructed and arranged to vary the terminal point of the 115 feeding movements imparted to said punch.

51. In a machine of the class described, the combination of a carrier, a punch sustained by said carrier, a feed slide and actuating devices therefor, a shaft having bear- 120

ing in the feed slide and provided with an eccentrically-located pin, means connecting said pin with the carrier, and means for turning said shaft.

52. In a machine of the class described, the combination of a carrier, a punch sustained by said carrier, a feed slide and actuating devices therefor, a shaft having bearing in the feed slide and provided with an eccentrically-located pin, means for connecting said pin and carrier, a pinion fast on said shaft, a rack meshing with said pinion, and mechanism for actuating said rack.

10 53. In a machine of the class described, the combination of a carrier, a punch sustained by said carrier, a feed slide and actuating devices therefor, a shaft having bearing in the feed slide and provided with an eccentrically-located pin, a link connecting said pin and carrier, a pinion fast on said shaft, a rack meshing with said pinion, and mechanism for actuating said rack.

15 54. In a machine of the class described, the combination of a carrier, a punch sustained thereby and arranged to feed the stock, a feed slide, actuating devices therefor, an adjustable connection between the carrier and feed slide constructed and arranged for operation to vary the terminal 20 point of the feeding movements imparted to said punch, and automatic mechanism for operating said adjustable connection.

25 55. In a machine of the class described, the combination of a carrier, a punch sustained by said carrier, a feed slide and actuating devices therefor, means for sustaining the feed slide including an oscillatory link, a shaft having bearing in the feed slide and provided with an eccentrically-located pin, means connecting said pin and carrier, a pinion fast on said shaft, a rack meshing with the pinion, a bell-crank lever pivotally supported on said link and having one arm connected with said rack, and 30 automatic mechanism connected with the other arm of the bell-crank lever and acting 45 to change the position of said pin to thereby vary the terminal point of the feeding movements imparted to the punch.

50 56. In a machine of the class described, the combination with means for alternately setting a plurality of kinds of fasteners in stock, of automatic mechanism for independently determining the distance that 55 said fasteners will be set from the edge of the stock.

57. In a machine of the class described, the combination with means for setting one kind of fasteners and for thereafter setting 60 another kind of fasteners in stock, of automatic mechanism for independently determining the distance that each kind of fasteners will be set from the edge of the stock.

65 58. In a machine of the class described,

the combination with means for setting first a plurality of one kind and then a plurality of another kind of fasteners in stock, of mechanism for determining automatically the distance that each kind of fasteners will be set from the edge of the stock, and means 70 under the control of the operator to vary the operation of said mechanism.

59. In a machine of the class described, the combination with means for setting first a plurality of one kind and then a plurality of another kind of fasteners in stock, of mechanism for determining automatically the distance that each fastener shall be set from the edge of the stock, and means under the control of the operator to vary the 80 operation of said mechanism.

60. In a machine of the class described, the combination with eyelet setting devices and lacing-hook setting devices and means for actuating said devices to alternately set 85 eyelets and lacing-hooks in stock, of an edge gage, and automatic actuating mechanism therefor constructed and arranged to control the distance that the eyelets and lacing hooks shall be set from the edge of the stock.

61. In a machine of the class described, the combination with eyelet setting devices and lacing hook setting devices and means for actuating said devices to alternately set eyelets and lacing hooks in stock, of an edge 95 gage and actuating mechanism therefor for determining automatically the distance that the eyelets and lacing hooks shall be set from the edge of the stock, and means under the control of the operator to vary the 100 operation of said mechanism.

62. In a machine of the class described, the combination of setting devices for two kinds of fasteners so located as to, respectively, occupy different lateral positions, mechanism for alternately actuating said devices, an edge gage, and mechanism acting automatically to locate said edge gage in operative relation to the setting device which is in operation.

63. In a machine of the class described, the combination with eyelet setting devices and hook setting devices so located as to, respectively, occupy different lateral positions, mechanism for alternately actuating said devices, an edge gage, and mechanism acting automatically to shift the edge gage laterally so that it will occupy an operative position relatively to the setting device which is in operation.

68 64. In a machine of the class described, the combination of eyelet setting devices and hook setting devices so located as to, respectively, occupy different lateral positions and actuating mechanism therefor, means for alternately rendering one of said devices operative and the other of said devices inoperative, an edge gage, and mechanism act-

ing automatically to move said edge gage into operative relation with each setting device as the same is actuated to set fasteners.

65. In a machine of the class described, 5 the combination of setting devices for two kinds of fasteners so located as to, respectively, occupy different lateral positions, mechanism for alternately actuating said devices, a punch and actuating mechanism 10 therefor constructed to make a hole in the stock and to feed the stock, an edge gage, and mechanism to control the position of the terminal point of the feeding movements imparted to the punch and to locate the edge 15 gage in operative relation to the setting device in operation.

66. In a machine of the class described, the combination of a carrier, a punch thereon, a feed slide and actuating devices therefor, means connecting said carrier and feed 20 slide including an adjustable member constructed and arranged to vary the position of the terminal point of the feeding movements of the punch, a supporting device 25 connected with said member for simultaneous movements therewith, an edge gage sustained by said device, and means confining the edge gage to said device for movements therewith while permitting movements 30 of the edge gage transversely of said device.

67. In a machine of the class described, the combination of a carrier, a punch thereon, a feed slide and actuating devices therefor, means connecting said carrier and feed 35 slide including a rotatable shaft having thereon an eccentrically-located pin, a crank connected with said pin, a slide bar pivoted to said crank and carrying spaced guides, 40 and an edge gage supported by the slide bar and arranged to play between said guides.

68. In a machine of the class described, the combination with devices for setting two 45 kinds of fasteners in stock, means for feeding the stock, and automatic mechanism for independently controlling the extent of such feeding movements relatively to each of said devices.

69. In a machine of the class described, 50 the combination with devices for setting two kinds of fasteners in stock, means for feeding the stock, automatic mechanism for independently controlling the extent of such feeding movements relatively to each of said 55 devices, and means under the control of the operator to vary the action of said automatic mechanism.

70. In a machine of the class described, 60 the combination with eyelet setting devices and lacing-hook setting devices, and means for feeding the stock relatively to said devices, of mechanism for independently controlling the spacing of the fasteners set by said devices.

71. In a machine of the class described, 65 the combination with eyelet setting devices and lacing-hook setting devices, and means for feeding the stock relatively to said devices, of automatic mechanism for independently controlling the spacing of the fasteners set by said devices, and means under the control of the operator to vary the action of said automatic mechanism.

72. In a machine of the class described, 75 the combination of eyelet setting devices and lacing-hook setting devices, means for feeding the stock, automatic mechanism, including a plurality of pattern cams, for independently controlling the extent of such feeding movements relatively to each of 80 said devices, and means for rendering any one of said pattern cams effective to govern the spacing of the fasteners.

73. In a machine of the class described, 85 the combination of eyelet setting devices and lacing-hook setting devices, means for feeding the stock, automatic mechanism, including a plurality of pattern cams, for independently controlling the extent of such feeding movements relatively to each of 90 said devices, and means for rendering any one of said pattern cams effective to govern the spacing of the fasteners, and manually controllable means to govern such spacings independently of said pattern cams. 95

74. In a machine of the class described, the combination of a punch, a feed slide connected therewith, means for supporting said feed slide to permit feeding movements thereof including a link, actuating mechanism for said feed slide including a member having a constant range of movement, and means connecting said link and member arranged for adjustment to vary the extent of the movements imparted to the feed slide. 100

75. In a machine of the class described, the combination of a punch, a feed slide connected therewith, means for supporting said feed slide to permit feeding movements thereof including a link, actuating mechanism for said feed slide including a member having a constant range of movement, means connecting said link and member arranged for adjustment to vary the extent of the movements imparted to the feed slide, and 110 automatic mechanism for controlling the position of said means.

76. In a machine of the class described, the combination of a punch, a feed slide connected therewith, means for supporting said 115 feed slide to permit feeding movements thereof, including a link, actuating mechanism for said feed slide including a member having a constant range of movement, a device connecting said link and member arranged for adjustment to vary the extent of the movements imparted to the feed slide, automatic mechanism for controlling the po- 120 125

sition of said device, and manually operable means to independently control the position of said device.

77. In a machine of the class described, the combination of a punch, a feed slide connected therewith, means for supporting said feed slide to permit feeding movements thereof including a slotted link, a cam disk having a groove therein, a slotted lever pivoted to the frame of the machine and provided with a roll to enter said groove, a connecting member located in the slots in said link and lever and arranged for adjustment therein to vary the extent of the movements imparted to the feed slide, and means for actuating said member.

78. In a machine of the class described, lacing-hook setting means including a plunger having a laterally-yieldable section constructed to support a hook, actuating means therefor, and means for positively actuating said section to free it from a hook after the setting operation.

79. In a machine of the class described, the combination of a raceway, a hook setting plunger having a laterally-yieldable section with hook supporting means thereon, actuating mechanism for said plunger, a member constructed and arranged to free said section from a hook, and a device actuated by said member for moving hooks from the raceway onto said hook-supporting means.

80. In a machine of the class described, the combination of a raceway, a hook setting plunger having a laterally-yieldable section with hook-supporting means thereon, actuating mechanism for said plunger, a lever provided with means for moving said section to free the same from a hook, an arm arranged above the raceway, a rotatable support for said arm, and means, including a connection between said lever and arm, arranged to effect upward and rearward movement of the arm as the lever moves forward, and downward and forward movement of the arm as the lever moves backward to sweep hooks from the raceway onto said hook-supporting means.

81. In a machine of the class described, the combination of a raceway, a hook setting plunger having a laterally-yieldable section with hook-supporting means thereon, actuating mechanism for said plunger, a lever provided with means for moving said section to free the same from a hook, an arm arranged above the raceway, a rotatable support for said arm, and means, including a yielding connection between said lever and arm, arranged to effect upward and rearward movement of the arm as the lever moves forward, and downward and forward movement of the arm as the lever moves backward to sweep hooks from the raceway onto said hook-supporting means.

82. In a machine of the class described, the combination of a raceway, a hook setting plunger having a laterally-yieldable section with hook-supporting means thereon, actuating mechanism for said plunger, a lever provided with means for moving said section to free the same from a hook, a pin pivotally supported by said lever, a spring-pressed link supported by said pin for sliding and pivotal movements, a stud pivoted to said link, an arm arranged above the raceway and provided with a sleeve to fit said stud, and a rotatable support for said arm, and means to lift the arm as the arm moves backward, and to permit it to move in close proximity to the raceway in order to sweep hooks therefrom onto the hook-supporting means as said arm moves forwardly.

83. In a machine of the class described, a hook-setting plunger having a pivotally connected section, hook-supporting means carried thereby, means for guiding said plunger, means for tilting said section to free the same from a hook, and a spring-pressed member located within the plunger and acting against the end of said section to return it to normal position when freed from the action of the tilting means.

84. In a machine of the class described, the combination with a laterally movable raceway, of a plunger having an eyelet setting device pivoted thereto, said device being provided with a spindle, and means for reciprocating said plunger and to thereby cause the eyelet setting device to first move laterally and pick an eyelet from the end of the raceway and to then move longitudinally and set the eyelet in the stock.

85. In a machine of the class described, the combination with a laterally movable raceway, of a plunger having an eyelet setting device pivoted thereto, said device being provided with a spindle, means for swinging said raceway to impale an eyelet upon the spindle, and means for reciprocating said plunger and thereby causing said setting device to first move laterally and pick the eyelet from the end of the raceway, and to then move longitudinally and set the eyelet in the stock.

86. In a machine of the class described, the combination with a laterally movable raceway and actuating means therefor, of a plunger, an eyelet setting device pivoted to said plunger, said device having a spindle and having also an angular extension beyond its pivot carrying a roll, a cam-way to receive said roll, and means for reciprocating said plunger, said raceway being arranged to be so moved as to impale an eyelet upon said spindle, and said cam-way being so shaped as to cause said setting device to first move laterally as the plunger rises and pick the eyelet from the end of the

raceway and to then move longitudinally and set the eyelet in the stock.

87. In a machine of the class described, the combination with eyelet setting means and hook setting means, mechanism to cause one of said means to set a plurality of fasteners and to then automatically stop the machine and thereafter to cause the other of said means to set a plurality of fasteners, and a manually operable member to restart the machine after the setting operation of the first-named means.

88. In a machine of the class described, the combination with eyelet setting means and hook setting means, of mechanism acting automatically to cause one of said means to set fasteners and to stop the machine, said mechanism acting to thereafter cause the other of said means to set fasteners, and controlling mechanism including a single manually-operable member for starting the machine after the operation of each of said setting means.

89. In a machine of the class described, eyelet setting means, hook setting means, automatic mechanism to cause a predeter-

mined number of operations of one of said means and stop the machine, and to thereafter cause a predetermined number of operations of the other of said means and stop the machine, and a single treadle and connections to restart the machine after each stop.

90. In a machine of the class described, the combination with automatic mechanism for successively setting eyelets and hooks in stock, of mechanism for variably determining the number of such eyelets and hooks to be set.

91. In a machine of the class described, the combination with automatic means for successively setting eyelets and hooks in stock, of mechanism for variably determining the number of each kind of said eyelets and hooks to be set.

In testimony whereof I have signed my name to this specification in the presence of two subscribing witnesses.

RALPH C. SIMMONS.

Witnesses:

LEONARD MATTHEW JOHNSON,
CHESTER EUGENE ROGERS.

Copies of this patent may be obtained for five cents each, by addressing the "Commissioner of Patents, Washington, D. C."

It is hereby certified that in Letters Patent No. 1,146,028, granted July 13, 1915, upon the application of Ralph C. Simmons, of Beverly, Massachusetts, for an improvement in "Hook and Eyelet Setting Machines," errors appear in the printed specification requiring correction as follows: Page 4, line 128, after the word "cam" insert the word *slot*; page 7, line 110, for the word "are" read *arm*; same page, line 114, for the word "arms" read *arm*; and that the said Letters Patent should be read with these corrections therein that the same may conform to the record of the case in the Patent Office.

Signed and sealed this 7th day of March, A. D., 1916.

[SEAL.]

Cl. 218-15.

J. T. NEWTON,

Acting Commissioner of Patents.
